UNITED STATES PATENT OFFICE.

ARTHUR H. HEDLY, OF CHICAGO, ILLINOIS, ASSIGNOR TO THE LUDLOW TYPOGRAPH COMPANY, OF CLEVELAND, OHIO, A CORPORATION OF MAINE.

METHOD FOR MAKING TYPOGRAPH MATRICES.

1,308,067.

Specification of Letters Patent.

Patented July 1, 1919.

Original application filed August 21, 1914, Serial No. 857,868. Divided and this application filed August 13, 1917. Serial No. 185,857.

To all whom it may concern:

Be it known that I, ARTHUR H. HEDLY, a citizen of the United States, and a resident of Chicago, county of Cook, and State of Illinois, have invented a new and useful Improvement in Methods for Making Typograph-Matrices, of which the following is a specification, the principle of the invention being herein explained and the best mode in which I have contemplated applying that principle, so as to distinguish it from other inventions.

The present improvements relate, as indicated, to the manufacture of matrices for typographs, and comprise more especially certain features of improvement disclosed in my copending application, filed August 21, 1914, Serial No. 857,868, (since issued into Patent No. 1,237,643, dated August 21, 1917), for manufacture of matrices for typographs, of which the present application is a division. These features refer primarily to the method of gaging the depth of the strike where such character-impressions are formed with the use of a punch.

To the accomplishment of the foregoing and related ends, the invention, then, consists of the steps hereinafter fully described and particularly pointed out in the claim, the annexed drawing and the following description setting forth in detail one mode of carrying out the invention, such disclosed mode illustrating, however, but one of various ways in which the principle of the invention may be used.

In said annexed drawing:

Figure 1 is a vertical sectional view of the bed of a driving press or punching machine adapted for the manufacture of matrices in accordance with my improved method; Fig. 2 is a perspective view of a blank matrix-bar or plate; Fig. 3 is a similar perspective view of such bar after it has been punched; Fig. 4 is a perspective view of the punch; and Fig. 5 is a side elevation of a punched bar or plate showing the method of gaging the strike of the punch.

The only portions of the general mechanism that require to be described, or even referred to, in the present connection are the bed 1 and punch head 7, these parts being relatively reciprocable so as to alternately advance and retract the punch B with respect to the matrix bar or plate A, shown as

held in operative position on the bed 1. The 55 details of the mechanism whereby successive bars A may be brought in position for punching, and there held in the manner illustrated in the figure in question, form no part of the present invention. The same is 60 true of the details of construction of the head 7 whereby the punch B is adjustably supported to vary the depth of the strike as well as to properly locate it with respect to the matrix bar or plate A.

The general form of the punch B employed in driving character-impressions into the blank matrix bars is indicated in Fig. 1, but shown in more detail in Fig. 4. From these figures it will be noted that the lower end 75 b of the punch is formed to enter the recess a in the opposed edge of the matrix bar (see Fig. 2), such recess being a characteristic feature of the particular bars in hand, and it being understood that the face of the 75 punch may be changed in form to suit the kind of matrix bar.

There will, of course, be a different punch for each character, and the body of such punch will correspond in its cross-sectional 80 dimensions with those of the matrix, being just a trifle less, so that the punch may move freely in the well or recess in the bottom of which the matrix blank is held gripped between the chuck jaws. As a matter of fact, 85 as explained before, it is the bed 1 of the machine, with such chuck jaws and matrix blank, that are moved relatively to the punch, rather than vice versa, the range of movement being slight, since it is only necessary to lower the blank sufficiently to allow the punch to clear the recess a in such blank, and thus permit of the insertion of a second blank after the character-impression has been struck in the first.

The upward movement of the bed of the machine carrying the blank, is limited by the engagement of the flat upper faces of the chuck jaws with a plate 60 secured to the under side of the head 7, and forming 100 part of the means whereby the punch is secured to such head.

In order to adjust the depth of the strike, since the bed and the head thus occupy a fixed relation at the end of the punching 105 stroke of the press, it is necessary to provide for the vertical adjustment of the punch. The plate 60, just referred to, is accordingly

slidably held in ways 61 in a second plate 62 directly attached to the under side of the head, said ways inclining slightly to the horizontal, as indicated in Fig. 1. The first-
5 named plate 60 is provided with an undercut slot 63 adapted to receive and slidably hold block 64 of T-shape, to which in turn is attached the punch B by means of a screw 65 passing through the upper end of the
10 same, and the depending portion of such block 64. Obviously if the slidable plate 60 be moved along its supporting ways 61 in the other plate, the punch and its supporting block being held against such movement
15 by reason of the engagement of the former in the well 17 between the chuck jaws, such punch will be slightly raised or lowered, depending upon the direction of movement of said plate 60.
20 Such movement is effected by means of a threaded spindle 66 rotatably but longitudinally immovably held in a bracket 67 attached to the front face of the head 7. The outer end of such spindle is provided with
25 a hand-wheel 68 to facilitate its rotation, while the threaded portion thereof engages with an upwardly projecting arm 69 on the plate. By means of such screw and the slight angle of the ways, it will obviously
30 be possible to secure a very fine adjustment of the punch vertically in the well, and thus obtain a strike of exactly the depth desired in the production of any given character impression. By providing a micrometer
35 scale (not shown) in connection with the wheel 68, or other movable part associated with the adjustment of the punch, the correct position of parts for any particular punch, once ascertained, can be readily re-
40 turned to when the punch is used again, such correct position being empirically determined in the first instance. In other words, the character impression is struck in the blank matrix, and the depth of such im-
45 pression is then carefully gaged by means of a suitable instrument, and the punch is thereupon adjusted, if necessary, until ex-
actly the right depth has been obtained.

Although reference is thus made to the
50 depth of the character impression, what I actually depend upon in manufacturing

matrices with my present improved mechanism, is the distance between the bottom of such impression and the back of the bar. In other words, I have found that it is 55 much more advantageous to measure the drive from the back of the bar instead of from its face. This distance a' (Fig. 5) being preserved accurately, the distance a^2 between the front and back faces of the 60 matrix bars may in turn be measured with reference to the same backs, and thus the depth of the impressions below the plane of such faces be likewise accurately determined. This method of gaging the location or depth 65 of the character impressions in matrices of the kind in hand, has, so far as I am aware, never been attempted before and permits the face of the matrix blank to be trimmed off after the intaglio character-impression 70 has been formed. It is, therefore, unnecessary to accurately gage the distance of such face from the back of the blank before the impression is formed by the punch, so long as a minimum distance between such face 75 and back is preserved in the original blank. The displacement moreover of the metal on the face adjacent the impression due to the action of the punch becomes a matter of indifference, since this is corrected in the final 80 operation of trimming the face.

Other modes of applying the principle of my invention may be employed instead of the one explained, change being made as regards the method herein disclosed, provided the steps stated by the following claim or the equivalent of such stated means be employed.

I therefore particularly point out and distinctly claim as my invention:— 90

The method of making matrices for typograph machines, and the like, which consists in driving a punch bearing a relief character into the matrix blank, gaging the depth of the strike with reference to the back of such 95 blank, and then trimming the face thereof back to a predetermined distance from such back.

Signed by me, this 9th day of August, 1917.

ARTHUR H. HEDLY.
